The ornamental design for a deadbolt with circular light, as shown and described.

DESCRIPTION

FIG. 1—is a perspective view of a deadbolt with circular light showing our new design;

FIG. 2—is a front view of the design shown in FIG. 1; FIG. 3—is a left side elevational view of the design shown in FIG. 1, the right side, top and bottom views being identical; and,

FIG. 4—is a rear view of the design shown in FIG. 1. The broken lines shown in the drawings are for purposes of illustrating portions of the design and form no part of the claimed design.
